United States Patent Office

Des. 213,040
Patented Dec. 31, 1968

213,040

JUG

Earl L. Schaper and Stanley A. Marcus, Midland, Mich.,
assignors to The Dow Chemical Company, Midland,
Mich., a corporation of Michigan

Original design application Jan. 3, 1966, Ser. No. 422,
now Patent No. 209,623, dated Dec. 19, 1967. Divided
and this application Aug. 4, 1967, Ser. No. 8,138

Term of patent 14 years

(Cl. D9—44)

Fig. 2

Fig. 1

FIGURE 1 is a side elevational view of a jug, showing our new design;

FIGURE 2 is a top plan view thereof;

FIGURE 3 is an elevational view thereof as seen from the left of FIGURE 1;

FIGURE 4 is an elevational view thereof as seen from the right of FIGURE 1;

FIGURE 5 is a fragmentary cross sectional view thereof taken along reference line 5-5 of FIGURE 2; and

FIGURE 6 is a fragmentary cross sectional view taken along reference line 6-6 of FIGURE 3.

The dominant features of our design reside in the portions shown in full lines.

This application is a division of application Ser. No. D. 422 filed Jan. 3, 1966, now United States Patent Number D. 209,623 granted Dec. 19, 1967.

We claim:

The ornamental design for a jug, as shown and described.
